UNITED STATES PATENT OFFICE.

CHRISTIAN G. SINGLEY, DECEASED, LATE OF MANHEIM, PENNSYLVANIA, BY
WILHELMINA A. SINGLEY, ADMINISTRATRIX, OF PHILADELPHIA, PENN-
SYLVANIA.

CIGAR CRIMPER.

Application filed August 4, 1925. Serial No. 48,130.

This invention relates to cigar crimpers, such as are adapted to form and close the mouthpiece end of cigars.

The primary object of the present invention is an improved cigar crimper comprising a thimble adapted to close the mouthpiece end of cigars and including an axially movable pin or needle adapted to form an axial hole centrally of the mouthpiece end without tearing, breaking or otherwise damaging the tobacco leaf wrapper.

A further object of this invention is a cigar crimper provided with a thimble for forming the mouthpiece end of cigars and including a pin or needle adapted to be forced through the centre of said end whereby the necessity for the user or smoker to cut, bite and chew the end of the cigar is eliminated.

A still further object of this invention is the production of a simple, inexpensive and labor saving cigar crimper adapted to form the head ends of cigars without the use of glue or paste and at the same time provide a vent hole so that the cigars will smoke freely.

With the above and related objects in view this invention comprises the construction, combination and arrangement of parts hereinafter more fully described, an embodiment whereof is illustrated in the accompanying drawing and is embraced within the scope of the appended claim.

In the said drawing:—

Fig. 1 is a side view of the cigar crimper.
Fig. 2 is a top view thereof.

Fig. 3 is a longitudinal section thereof.

Fig. 4 is a similar section showing the crimper in the process of crimping.

Referring more particularly to the drawing for a detail description of this invention, a cylindrical body 5 is provided at one end with a rounded off head 6 and at its opposite end it is provided with a thimble shaped surface 7. Inwardly of the surface 7 the body is provided with a cylindrical surface 8 extending inwardly of the contracted rim of the surface 7. Inwardly of the surface 8 the body is provided with a cylindrical surface of lesser diameter than that of the surface 8 and forming a shoulder 9. Inwardly of the shoulder 9 and extending through the rounded off head 6 the body is provided with a cylindrical surface 10 of a larger diameter

than that of the surface of the shoulder. A 55 rod 11 of a diameter slightly less than that of the shoulder 9 is provided at one end with a cylindrical shoulder 12, and extending outwardly of the shoulder 12 is a pin or needle 13. The end of the rod 11 opposite the needle end is threaded for the threaded recess of a cap 14 of a diameter slightly less than that of the surface 10. The portion of the body 5 of the cylindrical surface 10 is provided diametrically with an elongated 60 slot 16 for a rod handle 15 projected transversely through the cap 14.

A coil spring 17 is mounted inside the slotted portion of the body between the shoulder 9 and the cap 14.

The hereinbefore described crimper is assembled in the following manner:—First the spring is inserted through the rounded off head 6. The cap 14 is then inserted with its 70 recess inwardly of the body 5 and with ends of the rod 15 projecting transversely through the slot 16. The rod 11 is inserted through the thimble shaped opening with its threaded end inwardly of the body. The cap 14 is forced inwardly of the body compressing the spring 17, and while held in this position by means of the rod 15, the rod 11 is screwed on to the cap with its threaded 75 end inside the recess of the cap.

To finish the heads of cigars, the cigar 18 is inserted with its mouthpiece end inside the thimble shaped end of the crimper body 5 and while the crimper is held the cigar is turned, or the cigar may be held stationary and the crimper turned. This closes the end 80 of the cigar. While holding the cigar in the same position the cap is forced inwardly of the body causing the needle to pierce the end of the cigar inside the thimble. The cap is then released and the spring forces the 85 cap outwardly forcing the needle out of the end of the cigar. To cover the hole thus formed in the end of the cigar, either the crimper or the cigar may then be given another turn.

The finished cigar is now ready to be smoked, without cutting, biting or chewing on the mouthpiece end, since the ordinary pull on the cigar while lighting it will be sufficient to break the wrapper covering the 90 surface of the hole made by the needle.

What is claimed is:—

A cigar crimper and piercer comprising a

tubular body thimble shaped interiorly at one end and slotted transversely at the opposite end, an annular flange interiorly of the body intermediate said ends, the interior 5 diameter of the flange being smaller than that of the interior of the body, a rod inside the body projected through the flange and extended longitudinally of the slotted portion of the body, a pointed pin connected 10 with the rod and extended longitudinally between the flange and the thimble shaped end, a circular shoulder connecting the pin with the rod between the flange and the

thimble shaped end, a spring wound about the rod mounted inside the body between the 15 flange and the slotted portion of the body, a handle projected through the slot adapted to force the pin through the thimble shaped end of the body, said spring adapted to force the pin in the opposite direction. 20

In testimony whereof I have attached my force the pin in the opposite direction.

WILHELMINA A. SINGLEY,
Administratrix of the Estate of Christian G.
Singley, Deceased.
